STRAND DRYING APPARATUS

Pyam L. Pendleton, Cranston, R. I., assignor to
 Hampton Machine Company, a corporation of
 Rhode Island

Application April 6, 1948, Serial No. 19,305

7 Claims. (Cl. 34—69)

1

This invention relates to the processing of continuous strands of textile fibres. More particularly, it is concerned with a drying device capable of general use in series processes where a unit may consist of a reel on which yarn to be dried may be stored, the reel being manually retractable from a reel housing for initial loading, or for doffing or breakage repair to the yarn, after which the reel may be replaced in the housing for use as a component in the process in which, in normal operation, the yarn will enter the drier unit at one point with a high moisture content and leave at another point with a low moisture content, the extracted moisture being drawn off through the base of the drier unit by gravity or other means of conventional form, the time the yarn takes to follow a spiral path over the reel constituting the drying time.

Efficient operation of such a drying device requires that the major part of heat applied to the yarn from heat sources within the unit be effective in evaporating the moisture content of the yarn with a minimum of loss in conduction or radiation to the supporting and surrounding structures. At the same time it is desirable to employ high temperature heat sources in order to effect a high rate of heat transfer in a process where the yarn runs at a high rate of speed. Uniformity of the drying action requires a rapid modulation of heat transfer to the yarn in storage closely related to the quick starting and stopping of the yarn incidental to high production processes in conjunction with doffing or repairs to broken yarn strands. Heat transfer to the yarn must commence immediately the yarn is started in order to prevent the passage of improperly dried yarn and must cease immediately when the yarn stops in order to avoid scorching or burning the yarn in storage.

It is a principal object of the invention to provide a new, practical and efficient means, in a drying device of the type described, for using heat sources of relatively high temperatures, for example of the order of 800° F., closely adjacent to textile strands for high heat transfer purposes without damaging the yarn in fast stops and starts.

It is also an object of the invention to provide a drying device for continuous textile strands having a high rate of heat transfer in a compact structure while minimizing heat losses from conduction and radiation.

It is likewise an object of the invention to provide a drier unit capable of use in a series of treatments on a continuous yarn strand where

the requirements of heat transfer in the drier may be very rapidly modulated to correspond with fast starting and stopping desirable in any treatment of the series.

Another object of the invention is to provide a drier for use with a storage reel and housing wherein the heating elements are readily accessible for repair or replacement.

Still another object of the invention is to provide a drying device in which yarn stored on a reel in a reel housing may receive favorable coacting radiant heat reflection from closely spaced reflectors supported adjacent thereto.

It is also an object of the invention to provide a yarn drying device and method employing heating and centrifugal moisture removing means in alternation to achieve a more rapid and efficient drying action.

A still further object of the invention is to provide a drying device for use with a storage reel and housing wherein yarn on the reel may come into close relation with the heating elements yet be guarded against burning or scorching due to actual contact, and conversely, so that the elements will be protected from physical damage due to the presence of knots or tangles in the yarn.

Yet another object of the invention is to provide in a drying device including a storage reel, a reel housing and heat radiating elements requiring a closely spaced fixed operating relation, and where said spaced relation obstructs loading or servicing of the reel, means whereby the reel and reel housing may be separated in automatic conjunction with separation of the heat radiating elements to facilitate loading or servicing of the reel and thereafter automatically rejoined in conjunction with re-positioning of the heat radiating elements in the original relation.

With the foregoing objects in view, the present invention is featured by the provision of a source of radiant heat in a reel and cell assembly, said source being arranged in close proximity to a layer of traveling strand and having associated therewith reflecting means to focus the radiant heat on the fibres.

Another feature is the provision of an electrical grid of heating elements in a reel and cell construction, said elements being suspended in slots formed in a reflector whereby the fibres will be deflected from accidental contact with the heating elements.

Still another feature is the provision in a drying mechanism for the treatment of a continuous strand of textile fibres positioned in layer form

between a pair of oppositely disposed reflectors, of a grid comprising heating elements of small mass having low resistance connectors, cooperating with said reflectors to apply heat to said strand whereby an insignificant quantity of heat will be stored by the system and the application of radiant energy to the strand may be substantially instantaneously started or stopped by energizing or de-energizing the electrical heating elements.

Still another feature is the provision in a drying unit for a continuously moving stored yarn strand comprising heating elements and a storage reel in a housing adapted to reduce loss from heat radiation, of a semi-enclosed high temperature primary heating zone of relatively small area located in the interior of the housing where maximum heat transfer to the yarn strand takes place and where radiation and conduction losses in the primary zone are collected and utilized in a secondary heating zone to further the overall drying effect and efficiency.

Still another feature is the provision in a drying unit for receiving, storing, drying and delivering a continuously traveling yarn strand, said unit comprising a storage reel, a reel housing and a semi-enclosed area in the interior of the housing defining a heat transfer zone of relatively high temperature, of centrifugal means operating in a separate heat transfer zone of relatively low temperature to reduce the amount of moisture entering the primary zone thereby favorably reducing the amount of drying heat required with the centrifuged moisture draining from the reel housing without material evaporation.

With the foregoing and other objects and advantages in view, the invention consists in the novel arrangement and combination of parts as will be hereinafter more fully described in the following detailed description taken in connection with the accompanying drawings in which like numerals refer to like parts in the several views and in which:

Fig. 1 is a plan view, with portions broken away, of the cell and reel construction illustrating the arrangement of the heating elements;

Fig. 2 is a longitudinal section on line 2—2 of Fig. 1;

Fig. 3 is a transverse section on line 3—3 of Fig. 1, illustrating in particular the manner in which the electrical heating elements are arranged with respect to the other members;

Fig. 4 is a longitudinal section illustrating an alternative embodiment of the invention in which a single heating unit is employed to dry both layers of strand simultaneously; and

Fig. 5 is another alternative embodiment in which the heating elements are associated with the reel and the opposing secondary reflectors are carried by the cell walls.

Referring now more particularly to the embodiment of Figs. 1 through 3, the cell 8 having walls 9 is adapted to receive and support a loaded reel, which is not shown in detail, but which consists in general of two transversely spaced parallel supporting bars 10 on which a pair of longitudinally spaced rollers 12 and 13 is rotatably mounted. The reel may previously be loaded with a plurality of passes of continuous strand 18 of textile fibres, forming two oppositely disposed layers of yarn in a manner well known in the art. The cell 8 is adapted for the insertion and withdrawal of the loaded reel through the end thereof according to the usual practice, and may be provided with a conventional cover 51 and

drain 52, as shown in Fig. 4, for example. Any convenient arrangement of depending lugs 49 on the reel may engage grooved side bars such as 50 on cell 8 to maintain proper fixed operating spaced relations of the reel, cell and heater elements in assembly. The cell 8 may be associated with similar cells, not shown, placed in adjacent relation one to another so that strand may be passed through successive cells for treating, washing, rinsing, drying, etc. The present invention concerns itself, however, only with the drying operation which may be one of the above enumerated steps in the treatment or may be employed independently thereof.

- 15 Once the loaded reel has been inserted in the housing 8 the former may be driven at any desired speed through the sprocket 16 by a suitable drive (not shown). It will be seen that the strand itself will impart motion to the opposite roller 13 to drive the same at the same speed as the directly driven roller 12, and that strand may be continuously fed into one side of the reel, as at 18, and withdrawn, as at 20, for example. Conventional automatic switches may be employed to energize or de-energize the drier simultaneously with starting or stopping of the reel, and any well known automatic safety means may be employed for instantly halting the mechanism in case of yarn breakage.
- 20 According to the embodiments of Figs. 1 through 3, there is provided a heating unit 22 affixed to the walls 10 of the cell 8 by bolts 23, including electrical heating elements 24 of relatively light wire having both a high resistance and a high melting point, and reflecting plates 26. Duplicate units are provided in both sides of the cell. As best seen in Fig. 3, the individual heating elements 24 are held by connectors 28 at the end of the heating unit 22, said connectors having inwardly extending prongs or fingers 30 arranged in pairs so that the heating wires will be connected in series electrically. It will be observed that the individual mountings of the heating elements 24 on the fingers 30 enables the replacement of any individual element which may become burned out without disturbing the other elements.

Preferably the prongs or fingers 30 of the connectors 28 are of resilient material to accommodate expansion and contraction of heating elements while at all times preventing sagging of the wires 24. Likewise, the connectors 28 preferably are of high conductivity and small mass so that a relatively small amount of heat will be stored thereby during operation.

Each connector 28 is rigidly held by screws 32 to the outer surface of a reflector 26 and is properly insulated electrically. Insulated posts 33 are provided at the end of the unit 22 away from the connectors 28 to receive and support turns of the heating wires 24.

It is to be understood that the arrangement of straight resistance heating wires 24 may be supplanted by strips, ribbons or extended helical coils of metallic or non-metallic resistance material within the spirit and scope of the invention, except that where such a substitute resistance material has sufficient natural elasticity, resilience in the fingers 30 is of less importance.

At both ends of the reflectors 26 are provided insulated inwardly projecting guides 34 having V-shaped inwardly facing openings 36 for appropriately spacing the heating elements 24.

The inwardly facing surfaces of the reflector 26 are corrugated providing a series of grooves 38

of any desired contour to reflect the radiations of the elements 24 inwardly against the strand 14 while the lips thereof serve to deflect the traveling strand away from accidental contact with the heating elements 24 which are depressed in the grooves 38. As shown in Fig. 3, the slots 38 are rectangular in cross-section, but they may be arcuate or parabolic as desired. Optionally I may employ transparent sheets of heat resistant material or any other suitable deflecting means to shield the elements 24 from contact with the strand 14.

To the removable reel is affixed a pair of outwardly facing secondary reflectors 40 by means of bolts 42, arranged to match the reflectors 26 when the reel is inserted in the cell. The outwardly facing surface of each reflector 40 is adjacent and parallel to a plane tangential to both rollers 12 and 13 on the same side of the axed thereof. Thus when the reel is initially loaded with strand 14, the opposite layers of yarn are in close proximity and parallel to the reflectors 40. After the reel has been inserted in the cell container, the yarn travels in a path between the surfaces of the two reflectors 26 and 40 forming a primary heating zone adjacent the heating elements 24 and will be primarily dried by the radiant heat emanating and reflecting therefrom in conjunction with the heat conducted by air particles in intermittent contact with heaters 24 and yarn 14. After passing through the primary zone the strand enters a secondary heating zone in the area between the reel and housing which is heated by radiation and conduction losses from the primary zone and by the passage of the strand and accompanying circulating hot air particles. In this secondary zone, in addition to receiving heat by conduction which assists evaporation, excess moisture on the yarn in the form of drops or heavy water vapor is thrown off by centrifugal force in passing over rollers 12 and 13. This is of great importance to the overall drying efficiency as the first few turns of strand adjacent to the commencement of the strand helix on the reel usually have moisture content sufficiently high to be favorably affected by centrifuging action particularly when rolls 12 and 13 rotate at high speed. This mechanical extraction reduces the amount of moisture which would otherwise have to be evaporated by heat from the primary zone between reflectors 26 and 40. Moisture extracted in this manner will adhere to the walls of cell 8 and drain off through the drain 52 (shown in Fig. 4) which may be connected to conventional suction exhaust arrangements. By means of electrical connections, shown diagrammatically at 44, current is supplied from a suitable external source (not shown) to the series-connected heating elements 24.

In the embodiment of Fig. 4 there is illustrated a reel of the type in which the two layers of strand 14 are arranged in substantially a single plane, the inner course thereof traveling over rollers 46 and through a spacing comb 48. In this arrangement it is necessary to provide only one heating unit 22 which serves simultaneously to dry both layers of the traveling strand in an efficient manner. The secondary reflector 40 is arranged in the same manner as in the embodiment of Figs. 1 through 3. The reel illustrated in Fig. 4 is provided with a drain 52 and a cover 51 and is adapted for operation in a vertical position with the drain 52 lowermost. The embodiments illustrated in the other figures of the

drawings optionally may also be provided with covers and drains in like manner, although they have not been shown in the drawings.

In the alternative embodiment of Fig. 5 there is shown a conventional reel loaded with strand in two layers as in Figs. 1-3, but in this case the heating assembly has been reversed with the electrically-energized units 22 affixed to the reel while the matching secondary reflectors 40 are carried by the cell 18. This construction, however, may increase the weight of the reel and requires the use of detachable electric connections to permit loading and unloading of the reel and insertion and withdrawal thereof from the cell, whereas in the embodiments of Figs. 1-4 rigid conduit wiring may be employed.

It will thus be seen that I have provided a drier for yarn wound on a storage reel, making use of a grid of electrical resistance wire as a source of radiant heat, in which the temperature may be very rapidly raised or lowered concomitantly with stopping and starting of the yarn. The grid of light high resistance wires 24 is supported by adjacent heat reflecting surfaces of low mass which have a relatively low rate of absorption and low heat storage capacity and through connectors of low resistance and small mass which are not heated appreciably by passage of current, with the result that the areas of supporting structure in close proximity to the heat source do not store a harmful quantity of heat and do not radiate heat to the yarn in harmful quantity when the travel of the yarn is stopped and the current shut off, and furthermore do not cause a harmful lag in heat transfer when the yarn is started and the current again turned on. The arrangement of a primary reflector associated with the grid-supporting surface and a secondary reflecting surface opposed thereto serves to focus the radiant heat on the yarn passing therebetween to provide a highly efficient drying means with very little heat loss and a minimum of heat storage.

It is apparent that a drier may be constructed without the use of a secondary reflecting surface to match that of the grid support at a very considerable loss in efficiency. I prefer, however, to use cooperating pairs of reflectors to form a primary heating zone as distinct from a secondary heating zone between the reel and the reel housing to provide the highest degree of heating efficiency and the shortest time lag in temperature control when starting and stopping.

In the foregoing description I have illustrated preferred embodiments of the invention, but it will nevertheless be understood that my invention is capable of changes and modification and rearrangement of parts within the spirit and scope of the appended claims.

I claim:

1. A device for heat treating a traveling strand which comprises: a reel housing, a reel insertable therein, said reel being adapted to be loaded with a plurality of parallel passes of continuous strand to form a layer, an inwardly disposed heat reflector affixed within said housing and an outwardly disposed matching heat reflector carried by said reel to provide a cooperating pair of opposed parallel heat reflecting surfaces arranged to permit passage therebetween of said strand layer when said reel is inserted in said housing, and a source of radiant heat of low mass interposed between said surfaces and cooperating therewith to focus heat upon said layer.
2. A device for heat treating a traveling strand

which comprises: a reel housing, a reel insertable therein, said reel being adapted to be loaded with a plurality of passes of continuous strand forming layers thereon, an inwardly disposed primary heat reflector affixed to the interior wall of said housing and having an inwardly facing heat reflecting surface arranged to be adjacent and parallel to a strand layer when said reel is in inserted position, a grid of electrical heating elements mounted in said housing adjacent said primary reflector, and a secondary matching heat reflector carried by said reel beneath said strand layer and adapted to cooperate with said primary reflector and said heating elements to focus heat on said strand layer.

3. A device for heat treating a traveling strand which comprises: a reel housing, a reel insertable therein, said reel being adapted to be loaded with a plurality of passes of continuous strand to form two parallel layers, inwardly disposed grooved primary reflectors affixed to the interior walls of said housing and outwardly disposed matching secondary reflectors carried by said reel to provide two cooperating pairs of opposed parallel heat reflecting surfaces arranged to permit passage therebetween of the strand layers when said reel is inserted in said cell, and a grid of electrical heating elements associated with each of said primary reflectors, said elements being depressed in the grooves thereof.

4. A device for heat treating a traveling strand of textile fibers which comprises: a reel-supporting housing, a reel insertable therein, said reel being adapted to be loaded with a plurality of passes of continuous strand in layer form, a primary heat reflector carried by said reel having an outwardly facing heat-reflecting surface adjacent a strand layer, a secondary matching inwardly disposed heat reflector mounted on the interior of said housing, and a grid of electrical heating elements mounted on said reel adjacent the surface of said primary reflector, said reflectors and said grid being so disposed and arranged that when said reel is inserted in said housing a layer of strand will pass between said reflectors and adjacent said heating grid.

5. A device for heat-treating a traveling strand of fibers which comprises: a reel housing, a reel insertable therein, said reel being adapted to be loaded with a plurality of passes of continuous strand in layer form, outwardly disposed primary heat reflectors affixed to said reel and inwardly disposed matching secondary heat reflectors carried by said housing to provide cooperating pairs

of opposed parallel heat reflecting surfaces arranged to permit passage therebetween of a strand layer when said reel is inserted in said housing, and a grid of electrical heating elements associated with each of said primary reflectors and arranged adjacent said surfaces and cooperating therewith to focus radiant heat on the course of travel of said strand.

6. In combination with a drying unit for continuous textile strands having a storage reel housing, a storage reel separable therefrom and adapted to be loaded with a plurality of passes of strand to form a layer, and a heating unit consisting of a source of radiant heat and a pair of associated heat reflectors enclosing said layer, one of said reflectors being mounted on said reel and the other on said housing, means for retracting said reel from said housing concomitantly with separation of said reflectors to facilitate loading, replacement of and repairs to said yarn layer.

7. In a drying unit for continuous textile strands, a storage reel housing, a storage reel separable therefrom and adapted to be loaded with a plurality of passes of strand to form a layer, a heat reflector attached to said reel and a second heat reflector attached to said housing, said reflectors providing a coating pair of heat reflecting surfaces enclosing said layer when said reel is in inserted position, and heating elements associated with one of said reflectors, whereby said reflectors will be separated in conjunction with separation of said reel and housing to facilitate loading, replacement of and repairs to said strand layer.
